(57) **CLAIM**

The ornamental design for a motorized roller die cutting machine, as shown and described.

DESCRIPTION

FIG. 1 is a perspective view showing the top, left side and front of a motorized roller die cutting machine which forms our new design;

FIG. 2 is a left side elevational view thereof;

FIG. 3 is a right side elevational view thereof;

FIG. 4 is a top plan view thereof;

FIG. 5 is a rear elevational view thereof; and,

FIG. 6 is a front elevational view thereof.

Portions of the motorized die cutting machine shown in broken lines in the figures are for illustrative purposes only and form no part of the claimed design.
